UNITED STATES PATENT OFFICE.

PAUL BUTLER, OF LOWELL, MASSACHUSETTS, ASSIGNOR TO UNITED STATES CARTRIDGE COMPANY, A CORPORATION OF MASSACHUSETTS.

CARTRIDGE.

1,153,860.

Specification of Letters Patent. Patented Sept. 14, 1915.

Application filed January 15, 1914. Serial No. 812,203.

To all whom it may concern:

Be it known that I, PAUL BUTLER, a citizen of the United States, residing in Lowell, in the county of Middlesex and State of 5 Massachusetts, have invented an Improvement in Cartridges, of which the following description, in connection with the accompanying drawing, is a specification, like numerals on the drawing representing like 10 parts.

The present invention relates to a cartridge, and is embodied in what is commonly known as a paper cartridge, the purpose of the invention being to make the cartridge more nearly water-proof than has 15 been possible heretofore. In loaded cartridges of this type, the outer wad which confines the charge of shot is held in position by crimping in the outer end of the 20 paper tube. While the material of which the paper tube is made can be satisfactorily water-proofed so far as relates to its surfaces, it is practically impossible to protect adequately the cut end of the tube with 25 water-proof material, so that after the shell has been loaded and the cartridge completed, the said end, though forced tightly into contact with the surface of the wad is capable of absorbing moisture which gradually permeates the fiber between the 30 surfaces of the tube, causing the same to swell and become distorted. This swelling or distortion, though slight, is apt to be sufficient to prevent the ready insertion of the cartridge into the chamber of the gun, thus 35 rendering the cartridge practically useless.

The application of water-proofing material at the point of contact between the bent over end of the tube and the surface of the 40 wad has been found to be inefficient as an expedient for overcoming the trouble, in view of the fact that it is not durable enough to answer the purpose. Furthermore, any water-proofing material which can be used 45 for this purpose, such, for example, as paraffin, is liable to become chipped and broken out, leaving the cartridge in its original exposed condition.

In accordance with the present invention, 50 I provide the loaded cartridge with a relatively thin disk of paper, fiber, or like material, which is inserted in the muzzle end of the cartridge, between the surface of the

shot-confining wad and the outer end of the cup, after the latter has been turned over or 55 crimped to retain the wad in position.

The drawing is an elevation of a cartridge embodying the invention, the muzzle end thereof being broken away and shown in 60 longitudinal section.

The cartridge embodying the invention consists of the metallic cup 1 and the paper tube 2 the invention pertaining to a loaded cartridge as herein shown. The charge of powder, confined by one or more wads in the 65 usual way, is not herein shown, the charge of shot 3, however, being indicated as contained in the cartridge near the muzzle end thereof and confined as usual by the wad 4 held in position by the crimped in outer end 70 5 of the paper tube 2. Owing to the fibrous nature of the material from which the tube is made, it is practically impossible to protect the exposed edge of the tube where it has been cut to the right length and the fiber 75 may become more or less displaced or loosened when the end of the tube is turned over in the crimping process. There is, therefore, an opportunity for moisture to creep 80 in between the end of the tube and the surface of the wad; and owing to capillary attraction, the material is likely to absorb moisture enough to cause swelling or distortion.

In order to protect the exposed edge of 85 the tube, I provide the cartridge, in accordance with my invention, with a washer 6 which fits closely in the end of the cartridge beyond the wad 4, the said washer being 90 frictionally held in position by contact with the sides of the turned-in tube 2. In order to prevent undue back pressure against the shot at the time of discharge, I have shown the washer 6 as flexed in the middle so that the circumference of said washer while having a firm bearing against the bent in end of the paper tube does not extend far enough in to prevent the said bent end from straightening readily to release the wad 4 in response to the pressure of the gases. By 100 forming the washer in this way it can be held in place with a sufficient frictional hold to make a moisture proof end without materially increasing the back pressure and thereby injuring the efficiency of the cartridge. 105

What I claim is:

A paper cartridge comprising a metallic breech-cup and a paper tube, the said cartridge containing a charge confined therein by a wad held in position by the inturned edge of the paper tube at the muzzle end of the cartridge; combined with a relatively thin disk of water-proofed paper slightly larger in diameter than the cavity at the 10 muzzle end of the cartridge beyond the

outer wad, the said disk being concavo-convex in shape.

In testimony whereof, I have signed my name to this specification in the presence of two subscribing witnesses.

PAUL BUTLER.
